UNITED STATES PATENT OFFICE.

CLARENCE B. WESTON, OF MARION, OHIO, ASSIGNOR TO THE MARION STEAM SHOVEL COMPANY, OF MARION, OHIO, A CORPORATION OF OHIO.

TRENCH-DIGGING MACHINE.

1,247,191.

Specification of Letters Patent. Patented Nov. 20, 1917.

Application filed March 17, 1917. Serial No. 155,413.

To all whom it may concern:

Be it known that I, CLARENCE B. WESTON, a citizen of the United States, residing at Marion, in the county of Marion and State 5 of Ohio, have invented certain new and useful Improvements in Trench-Digging Machines, of which the following is a specification, reference being had therein to the accompanying drawing.

10 This invention relates to trench digging machines and the object of the invention is to provide a machine which will dig the trench, lay the pipe and fill the trench over the laid pipe; and which will deposit the 15 earth, removed in forming the trench, in that part of the trench in which the pipe has been laid, thus excavating the trench and filling the same with a single handling of the earth. A further object of the invention is to provide means whereby the 20 hoisting devices of the excavating mechanism may be utilized in laying the pipe, which is frequently of great weight. It is also an object of the invention to so construct the machine that the trench can be 25 dug and the pipe laid without the necessity of bracing the walls of the trench, thus effecting a great saving of time and money. It is also an object of the invention to provide 30 a mechanism of this kind in which an ordinary power operated shovel may be used as the excavating part of the mechanism.

In the accompanying drawings Figure 1 is a front elevation of a trench digging machine embodying my invention; Fig. 2 is a plan view of the truck showing the base of the excavating device thereon; and Fig. 3 is a longitudinal sectional view of the truck.

35 In these drawings I have illustrated one embodiment of my invention and have shown the same as comprising an elongated truck 1 adapted to span the trench and having its greatest length extending transversely to the trench. This truck is provided near its ends with rollers 2 by means of which it can be moved back and forth along the line of the trench. These rollers may be of any suitable character, but are, in the present construction, shown as having flanges to permit them to travel on rails.

By placing the supporting rollers near the ends of the elongated truck the weight of the truck, and the mechanism carried thereby, is located on the ground at points remote from the walls of the trench and consequently the vibration and strains due to the operation of the excavating mechanism are so far removed from the walls of the trench that they will not tend to loosen the earth and cause it to slide or cave into the trench. 55 Consequently I am able to dig trenches of very considerable depth without the use of bracing of any kind for the walls thereof. In this manner I not only save the time and material necessary to effect the bracing of 60 the trench walls, but I materially reduce the number of men necessary to construct the trench and lay the pipe. The truck may be of any suitable or preferred construction 65 and is here shown as rectangular in shape and as having front and rear girders 1^a, such as I-beams, which are connected one to the other at their ends by side girders 1^b. These girders are preferably braced by means of rods arranged diagonally of the respective 70 end portions thereof.

The excavating mechanism is mounted on this truck near its center so that it will be supported directly above the trench. In the present instance the excavating mechanism 80 comprises a rotary steam shovel of ordinary construction. A steam shovel of this kind comprises a base 3 having axles 4 adapted to carry ground wheels or track wheels, and has mounted on this base a revoluble platform 5 on which are mounted the power mechanism and the excavating devices. In the particular shovel here shown the power plant, which is not shown, comprises a steam boiler and steam engines, but, of course, it 85 will be understood that any suitable power may be employed. The excavating devices consist of a boom 6 on which is mounted a dipper arm 7 having at its lower end an excavating dipper 8 and which is operated in 90 the usual manner to excavate the earth along the line of the trench and to dump the same. This excavating mechanism may be mounted upon the truck in any suitable manner 95 and the truck here shown is provided with 100

transverse beams 9 arranged below, and secured at their ends to, the front and rear girders of the truck, preferably by means of clips, 10. These beams are provided with 5 recessed blocks, or bearings, 11, arranged to receive the axles of the steam shovel, from which the wheels have been removed, and these axles are firmly secured in the bearing blocks by means of clamping blocks, or 10 straps, 12, which are rigidly secured to the supporting beams by means of bolts 13.

In the operation of the machine, after a 15 section of the trench of suitable length has been dug the machine as a whole is moved rearwardly to the beginning of the section and the pipes are lifted by the hoisting mechanism of the steam shovel and lowered into the trench. This may be accomplished in various ways but a very convenient 20 device which can be readily attached to and detached from the excavating mechanism is shown in the drawings. This device consists in an elongated hook, or goose-neck, 14, to which is connected a short chain 15 having at its opposite end a ring 16 which may be slipped over one of the teeth of the dipper 8. This goose-neck is inserted into the pipe which is to be laid and the dipper is then operated in the usual manner to lift the 25 pipe and lower the same into the trench. This method of laying the pipe also facilitates the laying of the pipe to grade. By leaving a little loose earth in the bottom of the trench and then raising the pipe slightly and allowing it to drop a few times the earth 30 may be packed beneath the pipe to an extent necessary to bring it to the exact grade, and the packing of the earth will be sufficient to form a firm and uniform support for the pipe, which will not settle to 35 any appreciable extent. In laying the pipe along the excavated section of the trench the machine will have been moved to the forward end of the excavated section thereof 40 and when the last pipe is laid the machine is ready to again begin the excavating of another section of trench. As each dipper 45 of earth is removed from the trench the excavating mechanism is rotated through a half circle and the earth dumped into the trench in the rear of the truck, thus excavating the new section of trench and filling that section of the trench in which the pipe has been laid with a single handling of the earth. 50 When another section of trench of suitable 55 length has been excavated the machine is moved rearwardly and the pipe laid therein, and the described operations are repeated as the work progresses. The truck may be 60 moved along the trench in any suitable manner, but this can be accomplished without the use of additional mechanism by placing the dipper upon the ground at one side of the trench and then operating the crowding 65 mechanism on the boom to extend the dipper

handle. The dipper being held against movement the truck and the excavating mechanism carried thereby will be moved along the track. Inasmuch as the dipper can be placed on the ground either in front 70 of the truck or in the rear thereof it will be obvious that the truck can be moved in the desired direction.

The operation of the machine has been 75 fully described in connection with the description of the several parts thereof and it will be apparent that I have provided an excavating machine which is very simple in its construction and is of such a character that an ordinary power shovel can be used as the 80 excavating mechanism thereof, thus enabling a contractor, at a slight additional cost, to convert his power shovel into a highly efficient trenching machine. It will further be apparent that the operations of digging the 85 trench, laying the pipe and filling the trench are accomplished in such a manner that the work will proceed very rapidly and with great economy not only in time but in labor and in the saving of material. Because of 90 the construction of the machine it causes the strain to be placed upon the ground at points remote from the edges of the trench and there is very little likelihood of the walls of the trench caving in, as they are not 95 subjected to strain or vibration, but should there be a slide in the excavated section of the trench, before the pipe is laid, due to the character of the earth or other causes, the machine can be readily moved back into a 100 position which will permit this earth to be again removed by it. By eliminating the necessity of bracing the walls of the trench and by utilizing the hoisting devices of the 105 excavating mechanism to lay the pipe I am 110 able to operate the machine as a whole to dig the trench, lay the pipe and fill the trench with a very small number of men, and to accomplish the work much faster than it could be done with a larger number 115 of men by the old methods.

While I have shown and described one embodiment of my invention I wish it to be understood that I do not desire to be limited to the details of construction shown and described as various modifications will occur to a person skilled in the art.

Having now fully described my invention, what I claim as new and wish to secure by Letters Patent, is:—

1. In a machine for digging trenches, the combination with an excavating mechanism comprising a base having axles, a platform revolubly mounted on said base, and excavating devices carried by said platform, of a truck adapted to span the trench and of a length greatly in excess of the width of the trench, and devices carried by said truck to receive the axles of said base and firmly secure the same to the truck.

2. In a machine for digging trenches, the combination with an excavating mechanism comprising a base having axles, and excavating devices mounted on said base and capable of movement through an arc of 180 degrees, of a truck adapted to span the trench and of a length greatly in excess of the

width of the trench, and devices carried by said truck to receive the axles of said base and firmly secure the same to said truck. 10

In testimony whereof, I affix my signature hereto.

CLARENCE B. WESTON.
